UNITED STATES PATENT OFFICE.

THOMAS A. JENKINS, OF HOBOKEN, NEW JERSEY.

AUTOMATIC MILK-RECEIVER.

1,186,793.

Specification of Letters Patent. Patented June 13, 1916.

Application filed July 16, 1915. Serial No. 40,252.

To all whom it may concern:

Be it known that I, THOMAS A. JENKINS, a citizen of the United States, residing at Hoboken, in the county of Hudson and State 5 of New Jersey, have invented certain new and useful Improvements in Automatic Milk- Receivers, of which the following is a specification.

My invention relates to automatic milk receivers.

In the delivery of milk in bottles and the subsequent collection of the empty bottles, as is almost universally practised today, many disadvantages obtain. Frequently, 15 the filled bottles are surreptitiously taken from the consumer after having been properly delivered, thereby giving rise to considerable dissatisfaction, inconvenience and false accusations; the bottles usually occupy 20 a very conspicuous position on steps, porches, window sills and the like, which fact renders them very unsightly besides inviting the inadvertent knocking over and breaking of the bottles; and by reason of 25 such exposure the milk is subjected to extreme temperatures with the result that the bottles are often broken by freezing in the cold seasons, and the milk allowed to get so warm in mild seasons as to be unfit for im- 30 mediate consumption. I overcome these inherent disadvantages by the provision of a receiver in the form of a cabinet equipped with a door carrying locking mechanism co- 35 operating with a movable bottom or support for the bottles. The locking mechanism is designed to be arranged so that the milk dealer can have access thereto for the purpose of delivering the filled bottle and collecting the empty bottle, but permitting the 40 consumer, and he only, to open the door of the cabinet in order that the filled bottle may be removed. The movable bottom constitutes a detent upon which the bottle rests, the said detent controlling the door through 45 the medium of a vertically slidable bolt and a pair of horizontally slidable bolts, one of 50 which is operable by the dealer, to open the door so that an empty bottle may be removed and a filled bottle substituted there- 55 for, the door becoming automatically locked as soon as the filled bottle has been introduced into the cabinet and the door closed, while the other bolt carries a bolt-latch which can be actuated by the consumer only, entirely independent of the first mentioned bolt. In other words, the said bolt latch is

common to both of said horizontal bolts, but is controlled independently by said bolts, and one bolt is intended for the dealer only and the other is provided for the consumer 60 for use at all times. In order that the cabinet will be perfectly sanitary and to maintain a comparatively even temperature of the milk, I provide a filling of cement, a metallic lining and a plurality of ventilat- 65 ing openings.

To the accomplishment of the recited objects, and others coördinate therewith, the preferred embodiment of my invention resides in the construction and arrangement 70 shown in the accompanying drawings, hereinafter described and embraced within the scope of the appended claims.

In said drawings, Figure 1 is a front elevation of one of the cabinets embodying my 75 invention. Fig. 2 is a transverse section taken along lines 2—2 of Fig. 1. Fig. 3 is a vertical sectional elevation of the door and locking mechanism taken along lines 3—3 of Fig. 4. Fig. 4 is a fragmentary 80 view of the inside of the door showing the locking mechanism. Fig. 5 is a transverse section along lines 5—5 of Fig. 4. Fig. 6 is an enlarged detail sectional view of a portion of the bottom of the cabinet, and 85 Fig. 7 is a vertical transverse section taken along line 7—7 of Fig. 6.

Referring more particularly to the drawings for a detail description of my invention, the numeral 1 designates generally the 90 cabinet which may be supported in a manner similar to a letter-box or, as shown in the drawings, fixed directly to the wall of a house or dwelling. Either one or any number of cabinets may be employed as de- 95 sired. As will be noted in Figs. 2 and 6, the cabinet is provided with a compartment 2 having its vertical walls lined with sheet metal 3 and its bottom constructed of cement 4. I have also found it desirable to 100 utilize cement as a filling between the walls, as at 5, and to use an outside facing of wood 6,—all tending to produce a structure which will be sanitary and which will pre- 105 serve the milk at a comparatively uniform temperature. Further provision in this respect is made by the arrangement of a plurality of screened ventilating openings 7 ad- jacent the top of the door 8.

For certain advantageous reasons I have 110 found it desirable to construct the entire locking mechanism so that it will be primarily

- dependent upon the weight of the bottle. With this principle in mind I have countersunk a detent 9 substantially diametrically of the bottom 4 of the compartment, the inner terminal being pivoted as at 10, and otherwise provided with longitudinally extending ribs 11 on its under side which at their forward extremity merge into depending cams 12. A guide pin 13 projects transversely through an arcuate slot 14 in the cams and a lateral pin 15 protrudes from the base of the cams and is intended to ride over the inclined face of the vertical projections 16 of the slide 17. Both the detent 9 and the slide 17 are controlled by coil springs 18 and 19, respectively, the former passing through a slot 17' in the slide 17 and resting upon the base of the countersunk portion, while the latter is inclosed in a housing 19'.
 10 In order to operate the mechanism just described, the consumer first opens the door, as will be presently explained, this being compulsory because of the extension or lip 20 which is purposely formed on the lower edge of the door to preclude access to the operating end of the slide 17. With the door open the empty bottle is seated upon the detent 9 and the slide 17 is constrained inwardly against the tension of the spring 19, the projections 16 engaging the pin 15 carried by the cams 12 and consequently elevating the latter together with detent 9, of which it is an integral part, until the pin 15 falls into notches 21 of the projections 16.
 15 The detent 9 thereby assumes a position intermediate the positions shown by full and dotted lines in Fig. 6. Now the door is closed and only temporarily latched so that when the milk dealer arrives, he may open it and remove the empty bottle. As this is done, spring 18 will be forced to exert its maximum expansive force and accordingly push the detent upwardly in the position indicated by dotted lines in Fig. 6, while the spring 19 will simultaneously push the slide 17 outwardly until it occupies the position shown in full lines, whereupon a filled bottle is placed upon the bottom of the cabinet, the door closed, and the outer terminal 50 of the detent is engaged by a slot 22 in the confronting end of a plunger 23 mounted on the inside of the door. It will thus be seen that the detent is coupled with the door through the medium of the plunger 23, the function of which will shortly appear. It will also be seen that after the detent 9 enters slot 22, the said detent cannot move upwardly or downwardly, regardless of the position of the bottle. Consequently it will be impossible to open the door without using the proper key, or unless breaking the door is resorted to. If it were not for the presence of slot 22 in the end of the plunger, it would be possible to pierce the wire netting in front of the cabinet and with two fingers,

raise the milk bottles and thus allow the detent to become elevated and the plunger 23 to project inwardly. In this way the door could be easily opened without the use of a key.

The plunger 23 operates in a sheath 24 having a small spring 25 in its rear end. Extending vertically through a slot 26 in the sheath and connected to the plunger is a latch 27 designed to coöperate with the depending keeper 28 mounted on the lower end of a vertically slidable bolt 29. As best illustrated in Figs. 3 and 4, the bolt 29 is guided in its movement by means of the studs 30 and elongated slots 31, and has its upper extremity fashioned into a rack 32 which meshes with a pinion 33. Disposed at right angles to bolt 29 is another bolt 34, also provided with a rack for engagement with the pinion 33. In this connection, it will be pointed out that the pinion is formed of such dimensions as to accommodate both racks to a nicety. A companion bolt 35 is arranged coincident with the bolt 34 although its extremity adjacent the pinion does not coöperate therewith, but carries a tail-piece 36 which is in the path of movement of a tumbler 37 operable through the slot 38 by means of a suitable key. As exhibited in Fig. 5, the two bolts 34 and 35 are constructed so as to present a pair of housings 39 and 40 containing coil springs 41 and 42 which serve to restore the bolts to normal positions. The outer bolt 35 carries a pair of cover plates 43 to permit easy inspection of the springs, and the housings and cover plates as well as the intermediate reduced portions of the bolts are provided with alined slots 44 having pins 45 extending therethrough for the obvious purpose of guiding and bracing the bolts. A latch-bolt 46 is common to both bolts, and has a widened rear terminal 47 bearing against the coil spring 41. This latch-bolt may be manipulated in a retrograde direction by the movement of either bolt 34 or 35, by moving the knob 48 in the one instance and operating the tumbler 37 in the other instance. The shoulder 49 of the forward housing of the bolt 34 supplies the connection between the latch-bolt 46 and the bolt 34, while the shoulder 50 will serve to transmit movement from the bolt 35 to the latch bolt 46—these movements being manifestly independent of each other.

As previously explained, the plunger 23 remains coupled with the detent 9 after the door of the cabinet has been closed. In inactive position the plunger is extended beyond the plane of the door (see Fig. 3), but when brought in contact with the detent it recedes, and the latch 27 is in turn held in engagement with the keeper 28. With the several parts in the relation just set forth, the main latch-bolt 46 is projected beyond

the plane of the door behind the adjacent stationary frame—or in locked position. When the consumer desires to remove the bottle of milk he simply inserts a key in the 5 slot 38 and turns it so that the tumbler 37 will force the tail-piece 36 rearwardly whereupon the bolt 35 will move in the same direction and carry the latch bolt 46 with it. The filled bottle is then removed and re-
 10 placed by an empty one, as hereinbefore described. It will be understood that as soon as the dealer has completed his delivery, the lever will again spring outwardly and through the intermediate mechanism lock
 15 the vertical bolt against movement. Since the vertical bolt and the horizontal bolt 34 both mesh with the pinion 33, the bolt 34 cannot then be moved—and consequently the knob 48 and latch bolt 46 will remain in-
 20 active. In short, the only way in which the door can be opened when the cabinet contains a filled bottle is by resort to the proper key which is in possession of the consumer.

In broader aspects my invention comprehends the employment not only of the various means described but of equivalent means for performing the recited functions. It is desired to reserve the right to effect such modifications and variations as may come 30 fairly within the scope of the appended claims.

What I claim is:

1. In a device of the character described, the combination of a compartment adapted 35 to contain a receptacle or the like, a door for said compartment, locking means for the door, means for withdrawing said locking means, a detent for supporting the receptacle, and means for setting the detent 40 for rendering it inoperative, said means becoming automatically inactive so as to engage and render the withdrawing means inoperative by the removal of receptacle.

2. In a device of the character described, 45 the combination of a compartment adapted to contain a receptacle or the like, a door for said compartment, locking means carried by the door comprising a latch bolt, a pair of elements for independently operating said latch-bolt, a depressible detent beneath the receptacle and a slideable plunger engageable with said detent and cooperating with said locking means and adapted upon insertion of the receptacle and 55 closing of the door to render one of said elements inoperative.

3. In a device of the character described, the combination of a compartment adapted 60 to contain a receptacle or the like, a door for said compartment, locking means for the

door, a depressible detent disposed in the base of said compartment, a slideable plunger engageable with said detent and coöperating with said locking means, and means for elevating said detent to render it inactive, 65 said detent being caused to resume its normal set position in engagement with said locking means, upon insertion of the receptacle and closing of the door.

4. In a device of the character described, 70 the combination of a compartment adapted to contain a receptacle or the like, a door for said compartment, locking means carried by the door, a detent controlling said locking means when the door is closed and 75 said detent is supporting a bottle, a slide for initially setting said detent, and means carried by the door for preventing access to the slide when said door is closed.

5. In a device of the character described, 80 the combination of a compartment, a door for said compartment, locking means carried by the door comprising a latch bolt, a pair of relatively movable elements for operating said latch bolt, a bolt coöperating with 85 one of said elements, means actuated upon the insertion of a receptacle in said compartment and the closing of the door for rendering said bolt inoperative, and means for operating the other element at all times. 90

6. In a device of the character described, the combination of a compartment, a door for said compartment, locking means carried by the door comprising a latch bolt, a pair of relatively movable elements for operating said latch bolt, both of said elements being operable when the door is open, and means depressed by the inserted receptacle for rendering one of said elements inoperative, when the door is closed. 95

7. In a device of the character described, the combination of a compartment, a door for said compartment, locking means carried by the door, a latch associated with said locking means, withdrawing means for the 105 locking means, a spring actuated plunger connected with said latch, and a detent adapted to engage said plunger when the door is closed and the bottle is supported by said detent, said detent thereby rendering 110 the withdrawing means inoperative, and said latch being disengaged from said locking means when the door is open.

In testimony whereof I affix my signature in the presence of two witnesses.
